CLAIM

The ornamental design for an illuminator for a medical device or the like, as shown and described.

DESCRIPTION

FIG. 1 is a perspective view of an illuminator for a medical device or the like showing our new design;
FIG. 2 is another perspective view thereof;
FIG. 3 is a top plan view thereof;
FIG. 4 is a bottom plan view thereof;
FIG. 5 is a left side elevation view thereof;
FIG. 6 is a right side elevation view thereof;
FIG. 7 is a front elevation view thereof;
FIG. 8 is a rear elevation view thereof;
FIG. 9 is another perspective view thereof, shown in a position of use with a medical device;

FIG. 10 is another side view thereof, shown in a position of use with a medical device;
FIG. 11 is a perspective view of another illuminator for a medical device or the like showing our new design;
FIG. 12 is another perspective view thereof;
FIG. 13 is a top plan view thereof;
FIG. 14 is a bottom plan view thereof;
FIG. 15 is a left side elevation view thereof;
FIG. 16 is a right side elevation view thereof;
FIG. 17 is a front elevation view thereof;
FIG. 18 is a rear elevation view thereof;
FIG. 19 is another perspective view thereof, shown in a position of use with a medical device;
FIG. 20 is another side view thereof, shown in a position of use with a medical device;
FIG. 21 is a perspective view of yet another illuminator for a medical device or the like showing our new design;
FIG. 22 is another perspective view thereof;
FIG. 23 is a top plan view thereof;
FIG. 24 is a bottom plan view thereof;
FIG. 25 is a left side elevation view thereof;
FIG. 26 is a right side elevation view thereof;
FIG. 27 is a front elevation view thereof;
FIG. 28 is a rear elevation view thereof;
FIG. 29 is an exploded perspective view thereof; and,
FIG. 30 is another exploded perspective view thereof.
Broken lines immediately adjacent shaded areas represent bounds of the claimed design. Broken lines of the medical devices of FIGS. 9, 10, 19, 20, 29, and 30 are directed to environment. All other broken lines are directed to unclaimed features. The broken lines form no part of the claimed design.
